UNITED STATES PATENT OFFICE.

NELSON M. BAKER AND HAROLD K. PARSONS, OF SOUTHERBRIDGE, MASSACHUSETTS.

OPHTHALMIC MOUNTING.

1,245,998.

Specification of Letters Patent.

Patented Nov. 6, 1917.

Application filed February 23, 1915. Serial No. 9,850.

To all whom it may concern:

Be it known that we, NELSON M. BAKER and HAROLD K. PARSONS, citizens of the United States, residing at Southbridge, in the county of Worcester and State of Massachusetts, have invented certain new and useful Improvements in Ophthalmic Mountings, of which the following is a specification.

10 This invention relates to ophthalmic mountings, and has particular reference to that type of mounting embodying spring actuated nose engaging members which is commonly termed a finger-piece mounting.

15 The leading object of the present invention is the provision of an improved mounting of this character which will permit of the use of relatively large lenses and will attain what is commonly termed a short or narrow P. D., or in other words, in which a minimum separation of the proximate edges of the lenses will be required for accommodation of the parts of the mounting.

20 A further object of the present invention is the provision of an improved construction of guard lever arm which shall greatly facilitate the formation of the pivot bearing, while aiding in the attainment of the narrow P. D. of the mounting.

30 Other objects of the present invention include simplification of the various parts of the mounting and adaptations of the structure thereof, all working toward the attainment of the narrowest possible P. D. for the 25 mounting, and said objects and advantages should be readily apparent by reference to the following description taken in connection with the accompanying drawings, and it will be understood that we may make any 35 modifications in the specific details of construction shown and described within the scope of the appended claims without departing from or exceeding the spirit of this 40 invention.

45 Figure I represents a fragmentary view slightly in perspective of an ophthalmic mounting embodying our invention.

Fig. II represents a top plan view thereof.

Fig. III represents a plan view of one 50 form of lever arm blank.

Fig. IV represents a similar view of another view thereof.

Fig. V represents a similar view of a further modification.

Fig. VI represents a plan view of a guard 55 arm formed from the blank shown in Fig. III.

Fig. VII represents a fragmentary perspective view of one form of bridge and lens attachment. 60

Fig. VIII represents a perspective view of the parts at one side of the mounting in position for assembling.

Fig. IX represents a fragmentary front elevation of an extremely narrow P. D. 65 mounting.

Fig. X represents a plan view thereof.

Fig. XI represents an edge view of the parts, the bridge being shown in section.

In the drawings, in which similar characters of reference are employed to denote corresponding parts throughout the several views, the numeral 1 designates the lenses which are connected by the bridge member 2 bearing at its end the lens clips or attachments 3. In certain of the forms of the drawings we have shown the clip 3 as having ears embracing the sides of the lens and connected by a screw, or other fastening device, while in other forms we have illustrated what is known as a cement mounting, that is, one in which the lens clips and lens are connected without the use of mechanical fastening devices. 70 75 80

It will be noted that in the attainment of the narrow P. D. of our mounting the bridge 2 is preferably so shaped as to fit the crest of the nose of the wearer and is attached substantially to the front of the clip 3 so that the inner edge of the clip forms a continuation of the inner face of the bridge arch and is adapted to rest upon the nose and form a guard or bearing member. 85 90

It will thus be seen that the lenses are brought substantially into engagement with the nose, being separated therefrom at the most merely by the thickness of the strap portion of the lens clip. Consequently, a much larger lens may be employed than is possible with the at present common types of 95 mountings in which the seat for the guard arm pivot is located intermediate the inner curve of the bridge and the edge of the lens. In our construction to accommodate the pivot 4 for the lever arm, we dispose the 100 pivot seat or lug 5 either forwardly or rearwardly of the lens attachment, and laterally out of the curve of the arch of the bridge. 105

It will be understood, however that as illustrated in Fig. XI for example, the seat 5 in place of being substantially in alinement with the terminus of the bridge, may be disposed somewhat thereabove along the lens clip and at any desired position where the correct movement of the lever arm may be obtained. The main essential is that the pivot seat and pivot will be so disposed that it will in nowise interfere with the bringing in of the edges of the lenses toward the sides of the nose.

To obtain maximum travel of the guard in minimum space it is necessary that the material of the lever arm be disposed in a vertical in contradistinction to the horizontal plane usually occupied by said material. It is, therefore, necessary that some satisfactory pivot bearing be provided. In the ordinary types of construction this pivot bearing is provided by merely piercing the material of the lever arm. In the present form of construction, however, this is an impossibility, and the most desirable method is to in somewise form a tube with its axis parallel to the plane of the arm through which the pivot 4 may pass.

One of the main improvements of our present invention resides in the formation of this tube.

Figs. III, IV, and V illustrate three of the possible forms of blanks for obtaining the same result in the same manner. In each of these we have shown the blank as comprising the guard 6 at one end and the handle 7 at the other end, the arm preferably having the loop 8 formed intermediately therein to facilitate swinging of the arm in position, while intermediately along the arm is the extension or finger 9 adapted to be doubled, as indicated in Fig. VI, or to be bent downward at the offset 10, in the case of the form shown in Fig. IV, whereby this finger is brought to extend along one of the other portions of the lever arm. The material of the lever arm and the material of the finger are then each formed with the semi-cylindrical depression 11, as indicated in Figs. VI and VIII for example, the two depressions together providing the cylindrical aperture 12 to receive the pivot 4.

It will thus be seen that if desired the pivot bearing may be entirely formed simply by bending of the material without the use of solder or the like, or at the most it is merely necessary to solder the terminus of the finger 9 to the main portion of the lever arm, and that consequently a very satisfactory while inexpensive construction is provided.

Particular attention is invited to the structure illustrated in Figs. IX to XI, inclusive, in which it will be noted that the lens 1 has formed therein a slight recess as at 13, and

is additionally edged at a bevel or angle in place of flat edge as is customary. This type of construction is particularly adapted in connection with a thin cement strap lens attachment or the like which engages but a slight portion of the edge practically outside the field of vision. In this construction, as should be readily apparent by reference to Figs. X and XI particularly, the depth of the recess 13 is just sufficient to receive the lens attachment so that the bridge proceeds directly forward from the lens and the inner curve of the bridge is in alinement with the inner beveled curve of the lens, the lens thus being brought into actual engagement with the nose if so desired, while the width of the portion of the clip resting on the faces of the lens is so slight that the same would not be noticed by the wearer of the mounting. Consequently the mounting in nowise interferes with the vision. In this form of construction we have shown the pivot seat 5 as carried near the upper portion of the lens clip, the loop 8 in the lever arm curving upward along the edge of the lens in about the position indicated in Fig. IX for example, so that any required amount of movement may be given the guard arm without the same being brought into disagreeable contact with the sides of the nose.

The mounting just described is particularly desirable when properly fitted, since if the correct size and shape of bridge is employed the bridge, lenses and lens attachments may be all brought to fit against the nose and provide steadyng rests or bearings to insure exact correct positioning of the lenses before the eyes, while the guard member 6 serves merely as a gripping member to engage the nose to prevent tilting of the mounting thereon, much in the manner of operation of the temples in the ordinary spectacle mounting.

We claim:

1. A guard lever arm for a mounting of the character described, comprising a main arm having an offset, a supplemental finger formed integral with the offset, the said finger being doubled upon the arm and the arm and finger being shaped to form a tubular portion or pivot bearing substantially as and for the purpose described.

2. A guard lever arm for a mounting of the character described, comprising a main arm having an offset, said offset terminating at one end into a handle and the other end into a finger extending parallel with one portion of the arm, the said finger being doubled upon the handle portion of the arm and the finger and arm being shaped to form a pivot bearing.

3. A guard lever arm for a mounting of the character described, comprising a main arm and a supplemental finger integral

therewith, the said finger being doubled upon the arm and the arm and finger being shaped to form a tubular portion or pivot bearing, substantially as and for the purpose described.

4. A guard arm for a fingerpiece mounting, comprising a main portion and a finger bent to extend along the main portion and having its end secured to the main portion, the said finger and portion of the arm ad-

jacent thereto being spread to form a tubular bearing, substantially as described.

In testimony whereof we affix our signatures in presence of two witnesses.

NELSON M. BAKER.
HAROLD K. PARSONS.
